UNITED STATES PATENT OFFICE

100,272

DESIGN FOR A SHOE OR SIMILAR ARTICLE

Helen Kozak, Hollis, N. Y.

Application June 4, 1936, Serial No. 63,013

Term of patent 3½ years

To all whom it may concern:

Be it known that I, Helen Kozak, a citizen of the United States, residing in Hollis, in Queens County, in the State of New York, have invented a new, original, and ornamental Design for a Shoe or Similar Article, of which the following is a specification, reference being had to the accompanying drawing, forming part thereof:

I claim:

The ornamental design for a shoe or similar article, substantially as shown.

HELEN KOZAK.
